FIREPROOF IRON STAND.

Application filed September 7, 1926. Serial No. 133,947.

The present invention relates to ironing boards and more particularly to fire-proof iron stands in combination therewith.

The main objects of the invention are to provide a combination fire-proof iron stand and ironing board, to provide a permanently secured iron stand in combination with an ironing board and to provide a collapsible iron stand in combination with an ironing board whereby the stand can be extended when in use and collapsed when not in use.

The above objects may be attained by the device particularly described in the body of this specification and illustrated in the accompanying drawings in which:

Figure 1 is a plan view of the device.

Fig. 2 is a section thereof taken on line 2-2 of Fig. 1.

Fig. 3 is a perspective view of the assembled iron stand in collapsed position, the securing straps being broken off.

Fig. 4 is a perspective view of the unassembled parts constituting the iron stand.

The iron stand 1 is arranged in the pocket 2 of the ironing board 3 in such a manner as to provide a considerable air gap 4, surrounding the stand.

The iron stand, which is made of metal or other rapid heat dissipating material, comprises telescoping sections 5 and 6. The lugs 5' on the section 5 are adapted to slide horizontally in the slots 5'' of the section 6 and the lugs 6' on the section 6 are similarly adapted to slide in the slots 6'' of the section 5.

The supporting cross members 7 of the iron stand are spaced so as to provide ventilation for rapid heat dissipation and the ends and sides of the telescoping sections 40 provide walls to prevent the iron from slipping off the stand.

Means for securing the iron stand to the ironing board comprises a strap 8 made of rapid heat dissipating material which is rigidly affixed to the iron stand by rivets 9 and 45 the strap is secured to the ironing board as by the bolts 10. Washers 11 of non-conducting heat material, such as asbestos, are disposed interjacent the bolts 10 and the ironing board.

It will be observed that the air gap between the stand and the board provides an excellent heat insulator and that the material of which the stand is made, its open spaced sections and the asbestos washers, provide 55 means for rapidly dissipating the heat of an electric iron whenever the person using the iron leaves it and neglects to turn off the electric current. It will likewise be seen that the combination board and stand are 60 compact when not in use.

While but one specific embodiment of the invention has been herein shown and described, it will be understood that numerous details of the invention may be altered or 65 omitted without departing from the spirit of this invention as defined by the following claim.

We claim:

The combination with an ironing board 70 having a recess therein, of a collapsible metal iron stand arranged in said recess and comprising a pair of sections having substantially parallel fingers extending longitudinally of the board, the fingers of one 75 section being slidable longitudinally relative to those of the other section.

Signed at Portland this 30 day of August 1926.

ROBERT A. MORRISON.
